UNITED STATES PATENT OFFICE.

EARL R. JOHNSON, OF CHICAGO, ILLINOIS.

ADVERTISING NOVELTY.

Application filed October 4, 1926. Serial No. 139,325.

My present invention relates to an advertising novelty, produced in the form of a letter opening device with which is combined a holder for advertising matter or informative data, the object of my invention being to provide a simple and efficient device of this character which can be manufactured at low cost, and which is so constructed and arranged that the advertising matter or informative data can be readily removed and replaced from time to time as desired.

Other objects will appear hereinafter.

The invention consists in the combination and arrangements of parts hereinafter described and claimed.

The invention will be best understood by reference to the accompanying drawings forming a part of this specification, and in which

Fig. 1 represents a top plan view of an advertising device made in accordance with my present invention, parts being shown as broken away;

Fig. 2 represents an edge view of the device;

Fig. 3 is a cross section taken on the line 3—3 of Fig. 1;

Fig. 4 is a cross section taken on the line 4—4 of Fig. 1;

Fig. 5 is a plan view of a display slip;

Fig. 6 is a similar view of a transparent facing strip;

Fig. 7 represents a top plan view of a modified form of my device;

Fig. 8 is a partial edge and sectional view taken on the line 8—8 of Fig. 7;

Fig. 9 is a cross section taken on the line 9—9 of Fig. 7;

Fig. 10 is a plan view of the display slip; and

Fig. 11 is a similar view of the facing strip.

The preferred form of construction as illustrated in Figs. 1 to 6, inclusive, comprises an elongated body consisting of a blade portion 12 and a holder portion 13. The blade and holder portions 12 and 13 are preferably produced from a sheet metal form with the blade portion 12 offset laterally as at 14 from the holder portion 13.

According to a feature of my present improvements, the holder portion, considerably greater in transverse extent than the blade portion, has its free marginal edges upset into offset relation with one face of

the holder portion so as to provide therewith suitable seating spaces 15 for the reception of the marginal edges of the slips to be retained on the holder. In the present exemplification, the marginal edges of the holder portion are upset to provide opposed side flanges 16 and 17, a flange 18 at the free end of the holder and flanges 19 at the opposite edges of the blade portion. The side flanges 16 and 17 do not extend the entire length of the holder portion but terminate a distance from the flanges 19 so as to provide gateways 20 through which the slips to be retained may be entered into or removed from the seating spaces. 21 designates a strip of paper or the like containing the matter to be displayed and here shown as consisting of advertising matter 22 and a calendar 23. 24 designates a facing strip which may consist of transparent celluloid or other material suitable for the purpose. Both of the strips 21 and 24 should be sufficiently bendable to enable them to be readily passed through the gateways 20; it being observed that when inserting the said sheets behind the retaining flanges the ends 21' and 24' are first inserted through the gateways into the seating spaces and that when said ends 21' and 24' have been moved underneath the flange 18, then the ends 21'' and 24'' are bowed or flexed in the gateways until they can be slipped underneath the flanges 19. In removing the strips 21 and 24, the operation is reversed, namely, the ends 21'' and 24'' are flexed in the gateways 20 until they can be slipped from underneath the flanges 19, whereupon the strips may be drawn outwardly through the gateways 20. By this arrangement, the display slip may be removed and replaced whenever desired; it being the intention that the advertiser will supply the owner of the device with fresh slips from time to time.

In Figs. 7 to 11, inclusive, I illustrate a modified form, in which there is provided a holder portion 25 between the blade portion 26 and handle portion 27. These portions are of one piece, being produced from a single form of sheet metal. In this embodiment, the holder portion 25 extends well beyond the opposite edges of the portions 26 and 27 so that side flanges 28 may be bent into offset relation with the face of the holder. In this form also end flanges 29 are bent into offset relation with the face of

the holder. Between the side flanges 28 are gateways 30 through which the display strip 31 and its accompanying face strip 32 may be applied or removed. If desired, in either 5 of the forms herein illustrated, the facing strip may be entirely omitted.

While I have illustrated and described the preferred form of construction for carrying my invention into effect, this is capable of 10 variation and modification without departing from the spirit of the invention. I therefore, do not wish to be limited to the 15 precise details of construction set forth, but desire to avail myself of such variations and modifications as come within the scope of the appended claim.

Having described my invention, what I claim as new and desire to secure by Letters Patent is:

An advertising novelty comprising an envelope opener including a blade portion integral with a holder portion; opposing retaining flanges formed on the ends and sides of said holder portion and interrupted to provide a gateway, for a slip, with informative data, held in place on the holder by all of the retaining flanges and removable through said gateway, substantially as described.

In testimony whereof I have signed my name to this specification.

EARL R. JOHNSON.
